OSCAR PETERSON, OF CHICAGO, ILLINOIS, ASSIGNOR TO MILLS NOVELTY COMPANY, OF CHICAGO, ILLINOIS, A CORPORATION OF ILLINOIS.

BRAKE DEVICE.

Application filed July 20, 1925. Serial No. 44,767.

This invention relates particularly to a brake-device applied to music sheet-feeding mechanism.

The primary object is to provide an automatically actuated brake for sheet-feeding mechanism, such as sheet-feeding mechanism employed for feeding a music sheet in electrically operated musical instruments. More especially, it is the object of the present invention to provide mechanism of the character indicated with a brake which is automatically applied to the take-up roll after the playing operation has been concluded and previous to the rewinding operation and which is automatically withdrawn from the braking position previous to or at about the time the playing operation begins.

By means of the improved device, a desirable tension can be placed upon the music sheet during the rewinding operation, that is, while it is being rewound from the take-up roll onto the music roll, and, on the other hand, the brake is inactive during the playing operation, so that the motor does not need to overcome the retarding effect of the brake during the playing operation.

The sheet-feeding and rewinding mechanism may be of any suitable construction. It is preferred to employ sheet-feeding and rewinding mechanism of the type described and claimed in Sandell Patent 1,302,439, granted April 29, 1919. In this type of mechanism, a shaft driven from an electric motor and disposed in axial alignment with the take-up roll carries what is termed a compound dog, which, in the direct rotation of the motor drives the take-up roll through the medium of a crank with which its shaft is equipped, and, in the reverse rotation of the motor, engages a lug on a gear of a gear-train which drives the music roll and thus effects rewinding of the music from the take-up roll onto the music roll. Such mechanism is also equipped with a tracker-bar, or contact-roll, over which the music sheet passes and with which co-acts a series of electric contacts which control the circuits which operate various elements employed in the playing of the musical instrument.

As is well known in the art, a music sheet may be employed to control the playing of a piano, an organ, a stringed instrument of the violin class, or a combination of such musical instruments; and sheet-feeding and rewinding mechanism of the kind, for exam-

ple, shown in Sandell Patent 1,302,439 may be employed for effecting the feeding of the music sheet during the playing operation and then effecting the rewinding of the music sheet upon the music roll. The sheet-feeding mechanism described in the patent mentioned is capable of repeating its cycle of operations as long as power is supplied. That is, such mechanism will draw the music sheet from the music (storage) roll and wind it on the take-up roll during the playing operation, will then automatically rewind the music sheet on the music roll, then repeat the playing operation, etc.

The invention is illustrated in its preferred embodiment in the accompanying drawings as applied to sheet-feeding and rewinding mechanism of the kind disclosed in Sandell Patent 1,302,439, only so much of said mechanism being illustrated as is necessary for an understanding of the present invention. In the drawings—

Fig. 1 represents a broken front elevational view of sheet-feeding and rewinding mechanism equipped with the improved automatic brake; and Fig. 2 represents an end elevational view, partly in section, of said mechanism.

In the illustration given, A designates the frame of the sheet-feeding and rewinding mechanism; B, a music roll suitably journaled in the frame; C, a take-up roll; D, a metallic contact-roll, or tracker-bar; E, a music sheet which passes from the music roll in front of the contact-roll and thence to the take-up roll; F, a motor which operates through a worm-shaft F' and a worm-wheel F² to actuate a shaft F³ in either direction, depending upon the direction of rotation of the motor; F⁴, a compound dog of reversible character, which is fixedly secured on the shaft F³, being interposed between a crank G with which the shaft of the take-up roll is equipped and the lower gear of a gear-train H which serves to actuate the music roll B during the rewind operation, the compound dog F⁴ being thus in position to actuate the take-up roll C through the medium of the crank G during the playing operation and to actuate the music roll B through the medium of the gear-train H during the rewind operation; I, a contact-carrying insulation-bar mounted on a rock-frame I' which is supported on pivots I² (one shown), the rock-frame I' being

equipped with an actuating arm I^3 , through the medium of which the rock-frame may be turned on its pivots to bring the electric contacts which co-act with the contact-roll D and music sheet E to the operative position; J, a pivotally suspended foot, or link, which is connected by means of a pivot 1 with an arm 2 depending from the arm I^3 , the link J serving in the operation of lifting the arm I^3 to throw the contact-carrying bar I to the music-playing position; K, a latch link having a rearwardly curved upper end which is connected by means of a pivot-bolt 3 with the arm I^3 , the link K being provided at its lower end with a notch 4 which engages a stud 5 which projects from the end member of the frame A and thus supports the arm I^3 in its elevated position, in which position the contact-carrying bar I is held in the music-playing position; L, a spring-held trip-lever which is journaled on the stud 5 and which is equipped with a lug 6 adapted to engage the link K and release it from engagement with the stud 5 when the rotation of the motor is reversed, so that the arm I^3 will be permitted to drop and the contact-carrying bar I will be thrown to the inoperative position before the rewinding operation begins; M, a spring which tends to throw the arm I^3 downwardly and thus rock the frame I' about the pivots I^2 , said spring being operative to perform this function in retracting the contact-carrying bar I; N, a contact carried by the bar I and co-acting with the contact-roll D and thus serving to establish a circuit and effect reversal of the motor at the end of the playing operation, this action being accomplished by a slot (not shown) in the music sheet which is beyond the slots of the sheet which serve in the playing operation; and P, a switch-lever equipped with a roller P' which bears against the music sheet on the take-up roll C, the switch-lever P serving to effect reversal of the motor at the end of the operation of rewinding the music sheet from the take-up roll onto the music-roll, so that the motor will resume its direct rotation for the purpose of feeding the sheet in the playing operation.

The mechanism thus far described is constructed and operates in substantial accordance with Sandell Patent 1,302,439, to which reference is made.

The compound dog F⁴ which is secured on the shaft F³ and which serves in the direct rotation of the shaft in the direction indicated by the arrow in Fig. 2 to operate the take-up roll through the medium of the crank G, and in the reverse direction of rotation to actuate the gear-train H and through the medium thereof, the music-roll to effect rewinding of the music sheet, corresponds with the compound dog 87 referred to in said patent. This compound dog is.

provided with a reversible member 7 which is equipped with an arm 7^a which, when the shaft F³ rotates clockwise, as shown in Fig. 2, serves to engage and elevate the link J and thus lift the arm I^3 . This result is accomplished preparatory to the playing operation, the contact-carrying bar I being thus brought to the operative position. The reversible dog-member 7 corresponds with the member 92 of the patent mentioned. After the playing operation has been completed, the position of the dog-member 7 is reversed immediately after the motor starts to turn in the reverse direction, this reversal of the dog-member being effected by the trip-member L, whose movement is resisted by the spring 8 acting upon a suitable arm with which the trip-member is provided. When this action occurs, the arm 7^a finally moves the trip-member L far enough to cause the lug 6 to engage the lower end portion of the latch link K, thereby releasing said link from engagement with the stud 5 and permitting the arm I^3 to drop, thus carrying the contact-bar I to the inoperative position. The dog-member 7 is provided with an arm 7^b which is equipped on one side with a lug 7^c adapted to engage a lug, or wrist-pin, 9, which forms a part of the crank G, and which is equipped on the other side with a lug 7^d adapted to engage lug 7^e with which the lower gear of the gear-train H is equipped. The operation in this respect is fully disclosed and described in the above-mentioned patent.

The improved automatically applied and automatically released brake-device is designated R. It comprises a brake-shoe 10 which is adapted to bear against the adjacent flange of the lower spool, that is, the take-up roll C; a lever 11 which is suspended from a pivot 12 carried by the frame; a spring 13 connecting the lever with the frame and tending to throw the brake-shoe to the braking position against the flange 14 of the spool C; and a link 15 whose lower end is pivotally connected at 15^a with the short upper arm of the lever 11 and whose upper end is capable of sliding through a perforation in a lug 16 with which the arm I^3 is equipped. The upper end of the rod-like link 15 is threaded and equipped with nuts 17 above the lug 16. Thus, when the arm I^3 is lifted by the link J, the rod 15 will be lifted and will turn the lever 11 about the pivot 12 to the non-braking position shown in Fig. 1. This corresponds with the condition of the machine when the contact-bar I is in the operative position, that is, in the music-playing position. The brake-shoe 10 is at this time released from braking-engagement with the take-up roll C, so the take-up roll can be freely actuated by the motor during the playing operation.

The lower end portion of the lever 11 is 130

provided with an inturned arm 11^a which extends through a slot 18 with which the end frame of the machine is provided. The extremity of the arm 11^a is connected by a transverse pivot 11^b with the brake-shoe 10. The lower end portion of the lever 11 also carries the short outwardly extending arm 11^c which is provided with a perforation to which the upper end of the coil spring 13 is attached. By reason of the pivotal connection at 11^b, the brake-shoe is free to adjust itself so as to make full contact with the adjacent surface of the flange of the take-up roll.

For the purpose of the invention, it is unnecessary to illustrate and describe the electric circuits and devices for effecting the reversal of the motor and the driving of the motor in either direction. These electric circuits may be the same as those shown and described in the above-mentioned patent, or may be of any desired kind and arrangement.

It may be noted that the arm I³ which actuates the rock-member I' has a curved portion 19 extending through a perforation 20 in the adjacent frame-member. The manner of mounting the rock-member and of actuating it is substantially as shown in the patent mentioned.

From the description given, the operation will be readily understood. Assuming the mechanism to be in the position shown in Fig. 2, the device is ready for the playing operation. In Fig. 2, the arm 7^a of the member 7 of the compound dog F⁴ is about to pass from beneath the link J, which has been elevated during the initial portion of the rotation of the shaft F³ in a clockwise direction. As the direct rotation of the motor continues, the music sheet E is drawn from the music-roll B and wound upon the take-up roll C. It is to be observed that when the arm I³ was lifted by the link J, the rod 15 was raised, thereby swinging the lever 11 to the position shown in Fig. 1 and releasing the brake from engagement with the take-up roll. Thus, the take-up roll is free to be operated by the motor without retarding action by the brake. After substantially all of the music sheet has been transferred to the take-up roll, the contact N operates in a well known manner to close the circuit and effect reversal of the motor. This causes the shaft F³ to rotate in a counter-clockwise direction. When this occurs, the trip L reverses the dog-member 7, and the dog-member then operates through the trip to effect release of the lower end of the latch link K from the stud 5, thus permitting the arm I³ to drop under the action of the spring M. When this occurs, the contact-carrying bar I is thrown to the non-playing position. Also, the rod 15 drops with the arm I³, permitting the spring 13 to set the brake-shoe 10 against the flange 14 of the take-up spool. In the continued reverse rotation of the motor, the dog-member 7 of the compound dog F⁴, secured on the shaft F³, serves to rotate the gear-train H in a well known manner and thus cause the music-roll B to rotate in the proper direction to rewind the music sheet upon the music-roll. At the end of the rewind operation, the lever P operates to effect reversal of the motor and cause it to rotate in its original direction of rotation, that is, in the music-playing direction.

It may be noted that the free end of the lever P is equipped with a spring-held contact-member 21 which coacts with a contact-plate 22 in a suitable circuit; also the lever P, which is pivotally supported at 23 is equipped with a contact-stud 24 which engages a contact-pawl 25 whose outer end is supported on a stationary pivot 26. The contact N is connected by a conductor 27 with the contact-plate 22. The lever P is further connected by a conductor 28 with a spring-projected contact-member 29 which co-acts with a contact-member 30 carried by the rock-frame I'. The rock-frame I' is in electrical contact with the main frame, on which one side of the main circuit is grounded. When the contact N makes contact with the contact-roll D at the end of the playing operation, and while the contact-carrying bar I is in the playing position, reversal of the motor occurs. However, this interrupts the circuit at the point of contact between the member N and the roll D. The circuit is immediately re-established, however, by the contact-member 30, carried by the rock-frame I' engaging the contact-member 29. It should be borne in mind that this action occurs when substantially all of the music sheet is on the take-up roll C, at which time the right hand portion of the lever P, as shown in Fig. 2, occupies an elevated position, the pawl 25 being also lifted by the stud 24 and serving at a portion of the circuit as a conductor. The pawl 25 and the contact-plate 22 are connected by suitable conductors 31 and 32 with the same binding post of the motor (the connection not being shown, however). Thus, at the end of the playing operation, current may pass from the brush N through the conductor 27 to the contact-plate 22 and thence to the motor in a direction to reverse the motor; and after the brush N has been withdrawn from the contact-roll D, current may pass from the frame of the machine through the contact-member 30 to the contact-member 29, thence to the lever P, contact-stud 24, pivoted contact-member 25, and conductor 31 to the same binding-post of the motor. Eventually, the contact-member 21 is brought into fully established contact with the plate 22,

and the pawl 25, supported by a stud 33, ceases to contact with the contact-stud 24 of the lever P. The circuit is now carried wholly through the contact-member 21 to the contact-plate 22 and thence to the motor. Finally, the contact-member 21 will spring past the contact-plate 22, and the circuit will be broken. This type of circuit-controlling device may be employed in connection 10 with a motor having a weak field for direct operation of the motor and having a stronger field which will dominate and overcome the weak field in the reverse operation of the motor, that is, when the rewinding is 15 being effected. On the other hand, if desired, the electric circuits and controlling devices may be the same as those shown in the above-mentioned Sandell patent.

The present invention constitutes a modification of the invention described in my pending application No. 97,004, filed March 24, 1926.

The foregoing detailed description has been given for clearness of understanding 25 only, and no unnecessary limitations should be understood therefrom, but the appended claims should be construed as broadly as permissible, in view of the prior art.

What I regard as new, and desire to secure by Letters Patent, is:

1. In means of the character set forth, a reversible motor, a contact-carrying bar, a rock-frame on which said bar is mounted equipped with an actuating arm, means 30 driven by said motor for lifting said actu-

ating arm, a braking device co-acting with the take-up roll of the mechanism, a spring normally tending to apply said braking device and retracting means for said braking device actuated by the actuating arm of said 40 rock-frame.

2. In means of the character set forth, the combination with sheet-feeding and rewinding mechanism comprising a music-roll, a take-up roll, and a reversible electric motor 45 for driving the rolls of a brake-shoe adapted to press against the end of the take-up roll, a lever carrying said brake-shoe, a spring normally tending to apply braking pressure through the medium of said lever, 50 and motor-actuated means for retracting said lever.

3. In means of the character set forth, the combination with a frame, sheet-feeding and rewinding mechanism comprising a 55 music-roll, a take-up roll, and a reversible electric motor for driving the rolls, of a lever supported on a pivot parallel with one end of the frame, said lever having an inwardly extending arm, a brake-shoe pivotally 60 mounted on said arm and adapted to engage the take-up roll, a spring tending to throw said brake-shoe to the braking position, a latch restraining said lever from applying the brake during the playing operation, and 65 motor actuated means adapted to retract said latch after reversal of the motor at the end of the playing operation.

OSCAR PETERSON.
